UNITED STATES PATENT OFFICE

2,002,030

FURNACE

Walter Grothe, Alameda, Calif., assignor to Caterpillar Tractor Co., San Leandro, Calif., a corporation of California

Original application July 9, 1928, Serial No. 291,322. Divided and this application May 4, 1931, Serial No. 534,905

4 Claims. (Cl. 263—10)

The invention relates to furnaces, and particularly to a door therefor.

The object of the invention is to provide an improved door structure for a furnace.

5 This application is a division of application Serial Number 291,322, filed July 9, 1928, which issued as Patent No. 1,825,059, dated September 29, 1931.

Description of figures

10 Fig. 1 is a sectional view of a furnace in which the improved door is installed.

Fig. 2 is a front elevation of the furnace with the shell broken away to show the door structure, with the door in the closed position.

15 Fig. 3 is similar to Fig. 2 with the door in the open position.

Fig. 4 is a sectional view of the door operating mechanism taken on line 4—4 of Fig. 3.

Description of mechanism

20 Access to the interior annular chamber 31 within which are placed the articles to be treated, is afforded through a sliding door. This door preferably comprises a block 91, made up of suitable insulating material, adapted to slide vertically in an opening 92 provided in the shell 6. The block 91 is vertically reciprocated by a pair of rods 93 at their lower ends joined by a cross member 94 and sheathed in guiding tubes 96. The vertical movement of the rods and of the door is adjustably limited by an auxiliary rod 97 carrying adjusting nuts 98 forming a stop. The rod passes through an aperture in a portion of a frame 99 secured to the shell.

25 In order to counterbalance the weight of the block 91 and its operating mechanism, cables 101 are preferably secured to the cross member 94, pass over pulleys 102 journaled in the shell 6 and carry counter-weights 103 at their opposite ends. The cross member 94 is vertically translated by a lever 104 joined to it by links 106 and rotatable with a shaft 107 suitably journaled on the shell 6. The end of the shaft 107 carries a handle 108 conveniently disposed for actuation by the operator. Preferably the relationship and adjustment of the actuating linkages for the door 91 are such that the top of the door when lowered

is exactly flush with the floor of the opening 92, as indicated by the dotted lines 109 in Fig. 1. Thus there is formed a continuous and smooth passageway for the materials being inserted into or withdrawn from the furnace. Further, by 5 arranging the door 91 to move downwardly when being opened, it is possible to utilize full insulation above the door where large heat losses would otherwise occur.

I, therefore, claim as my invention:

1. A furnace comprising a shell having an opening therein and insulation projecting outwardly above said opening, a door vertically slidably across said opening and adapted to close the opening when the door is in an upper position with the top thereof adjacent said insulation, and means for moving said door from said upper position to a lower position, said top of the door being adapted to register with the bottom bounding said opening when the door is in the lower 20 position.

2. A furnace comprising a shell having an opening therein and insulation projecting outwardly above said opening, a door vertically slidably across said opening and adapted to close the opening when the door is in an upper position with the top thereof adjacent said insulation, means for moving said door from said upper position to a lower position, said top of the door being adapted to register with the bottom bounding said opening when the door is in the lower 25 position, and a stop for maintaining said top and bottom in registry.

3. A furnace comprising a shell having an opening therein and insulation projecting outwardly above said opening, and a door movable with respect to said opening and adapted to close the opening with the door top adjacent said insulation.

4. A metallurgical furnace comprising a shell 40 having an opening therein and insulation projecting outwardly adjacent a bounding surface of said opening, and a slidably mounted door movable with respect to said opening and adapted to close said opening with an edge of the door 45 beneath and adjacent said insulation.

WALTER GROTHE.
